FLOW-MOTOR

Arthur R. Pangborn, Watkins Glen, N. Y.

Application March 27, 1933, Serial No. 663,028

8 Claims. (Cl. 236—25)

This invention is a control device, the same being especially adapted for controlling the supply of fuel to a burner, and more particularly to a burner forming part of a steam generator of a type for which this invention is especially designed.

Briefly the invention consists in the provision of a control device for disposition within a fuel line connected with a burner and consisting in a construction, combination and arrangement of elements as to be substantially automatic in operation, being controlled solely by pressure in a manner to insure a cut off of the flow of gas to the burner in the event, from one reason or another, the supply of water to the generator is materially reduced or completely shut off.

The invention together with its numerous objects and advantages will be best understood from a study of the following description, taken in connection with the accompanying drawing wherein is illustrated the preferred embodiment of the invention.

It is to be understood at the outset that the embodiment of the invention herein illustrated and described is in no wise intended to be restrictive, and that it is intended to limit the invention only in accordance with the requirements of the prior art and scope of the appended claims.

In the drawing:

Figure 1 is a vertical sectional view through the device with the same shown in closed position, and

Figure 2 is a horizontal sectional view through the device, the same being shown in an open position.

Referring to the drawing by reference numerals it will be seen that the device comprises a substantially cylindrical casing comprising a body or intermediate portion 5 having removable top and bottom sections or caps 6 and 7 respectively secured to the intermediate or body section 5 through the medium of bolts or other fastening elements 8.

The body or intermediate section 5 has an opening 9 therethrough and at each end of the opening is provided with a concavity 10 and 11 respectively. The top and bottom or cap sections 6 and 7 are hollow and provide pressure chambers 12 and 13 respectively separated from the concavities 10, 11 through the medium of diaphragms 14 and 15 respectively clamped between the sections 5, 6 and 7 as shown in Figure 1.

Mounted for reciprocation within the opening 9 of the body section 5 is a piston 16 having

its ends 10 extending through apertures in the diaphragms 14, 15 and engaged with said pin or washers 17 and nuts 18.

At diametrically opposite sides thereof the body section 5 of the casing is provided with inlet and outlet ports 19, 20 having respectively restricted inner ends 21, 22. Pipe sections 23, 24 forming part of a fuel line have ends threaded with the ports 19, 20 for connecting the device in the line between the source of fuel supply and the burner.

The ports 19, 20 are controlled by the piston 16 which is provided intermediate its ends with a peripheral groove forming a fluid passage 25 for movement into and out of registry with the ends 21, 22 of the said ports 19, 20.

Pressure chambers 12 and 13, are connected through the medium of an axial passage 26 provided in the piston 16 and operating in the passage 26 is the elongated stem 27 of a relatively stationary valve 28 normally seating at the lower end of the passage 26.

Swivelly connected with the valve 28 is an adjusting bolt 29 screw threadedly engaged with the cap 7 and equipped with a lock nut 30. Mounted on and secured to the cap 6 in any suitable manner, preferably as by being integral therewith is a dome 31 in which is arranged a coil spring 32. The coil spring 32 has its lower end seating against the washer 17 associated with the pin provided at the upper end of the piston 16. The upper end of the spring 32 seats against the head of an adjusting screw 33 that is threadedly engaged with the crown or top of the dome 31; and a lock nut 34 is associated with the screw 33 as shown. Obviously through the medium of the screw 33 and lock nut 34 the tension of the spring 32 may be adjusted as found desirable.

The chamber 13 is provided with a water inlet and threadedly engaged in the inlet of the chamber 13 is one end a pipe section 35 forming a water conduit leading from a suitable source of supply. The chamber 12 is provided with a water outlet and screw threadedly engaged with the outlet of the chamber 12 is one end of a pipe section 36 that is, in the present instance intended to connect the chamber with the generator or similar device with which the invention is to be associated in actual practice.

From the description of the invention thus far it will be seen that the device, with the parts in the position shown in Figure 1 is normally closed. Assuming that water is supplied to the chamber 13, it will be apparent that when the pressure in the chamber 13 is built up sufficiently diaphragm

15 will be flexed upwardly causing the piston 16 to move upwardly and the diaphragm 14 to also correspondingly flex upwardly until the passage 25 is in registry with the ends 21, 22 of the ports 19, 20. With the passage 25 in registry with the said ports, fuel, assuming the same in the present instance to be gas, will pass from the port 19 around the passage 25 to discharge from the device through the port 20 and to be carried through the medium of the pipe section 24 to the burner. Upward movement of the piston 16, which movement is of course relative to the valve 28 will permit water from the chamber 13 to pass upwardly through the passage 26 into the chamber 12 and from the chamber 12, through the conduit 36 to the generator.

When the back or generator pressure in the chamber 12 nearly equals the water pressure in the chamber 13 the action of the spring 32 together with the pressure in the chamber 12 will act on the diaphragm 14 to restore the same to its normal position causing the piston 16 to move downwardly thus closing the port 19, 20 and arresting or stopping the flow of fuel through 25 the device to the burner.

From the foregoing it will be seen that the device acts in response to pressure, is substantially automatic in operation, and when used in conjunction with, for example, the generator for controlling the supply of fuel to the burner of the generator, will prevent any damage to the generator since, as is thought apparent, unless there is water flowing into the generator there can be no fire under the generator, as the absence 30 of the water flow will result in an automatic closing of the ports 19, 20 and a consequent cut off of the flow of fuel to the burner.

As is thought apparent the tension of spring 32 may be adjusted as to maintain the proper 40 balance at various water pressures; while the valve 28 through the medium of its connection with the screw 29 may be readily adjusted axially relative to the piston 16.

When the device is in a closed condition gas 45 in the inlet side thereof is permitted to leak from the ports 19 to a passage 37 into the chambers formed by the cavities 10, 11, passage 37 connecting the port 19 with said cavity.

While I have herein referred to the device as 50 being especially adapted for use in connection with generators it is to be understood that I am aware of the utility of the devices other than just stated and accordingly the use herein mentioned is not intended to be restrictive, but only 55 exemplary.

Having thus described my invention, what I claim as new is:

1. In a flow control device of the class described, a casing provided with a fuel inlet and 60 a fuel outlet port, a piston mounted for reciprocation within said casing and provided with a passage for connecting said ports, pressure chambers provided above and below said ports a water inlet and outlet connected respectively 65 with said chambers, diaphragms in said chambers connected with said piston, and said piston having a passage therethrough connecting said chambers and valve means part of which is connected with said piston and part with said casing 70 for controlling communication between the passage in said piston and one of said pressure chambers.

2. In a device of the character described, a 75 casing provided with a fuel inlet port and a fuel outlet port, a piston mounted for reciprocation

within said casing and having a passage for establishing communication between said ports, upper and lower pressure chambers said casing having water inlet and outlet ports in communication respectively with said chambers, diaphragms mounted in said chambers, operating connections between said diaphragm and said piston for controlling the movement of the latter, an axial passage in said piston connecting said pressure chambers and said water inlet and outlet ports, a spring device in one of said chambers and acting on said piston to normally move the same in one direction, and a valve member adjustably mounted in the other of said pressure chambers in operative position and against which the piston at one end of said axial passage is adapted to seat when the piston is in one position.

3. In a device of the character described, a flow control for a fuel feed line including a casing 20 a reciprocating piston, and pressure responsive means at opposite ends of the piston for actuating it and including pressure chambers one of which is provided with a water inlet, and the other of which is provided with a water outlet, a 25 passage extending through the interior of said piston and from end to end thereof, and valve means attached to said casing and said piston for controlling said passage.

4. In a device of the character described, a 30 casing provided at one end with a water inlet, and at a relatively opposite end with a water outlet, and being also provided intermediate said ends, and on one side with a fuel inlet port, and on a side opposite to said inlet port with a fuel 35 outlet port, spaced diaphragms mounted in said casing, a piston between said diaphragms and connected therewith, said pistons being provided with a passage for establishing communication in said fuel inlet and outlet port, and being also 40 provided with a second passage for the circulation of water from the water inlet of the casing to the water outlet of the casing and a valve for closing one end of the second named passage in said piston mounted within one end of the casing. 45

5. In a device of the character described, a 50 casing provided at one end with a water inlet, and at a relatively opposite end with a water outlet, and being also provided intermediate said ends, and on one side with a fuel inlet port, and on a side opposite to said fuel inlet port with a fuel 55 outlet port, spaced diaphragms mounted in said casing, a piston between said diaphragms and connected therewith, said piston being provided with a passage for establishing communication in said fuel ports and being also provided with a second passage for the circulation of water from the water inlet at one end of the casing to the water outlet at the other end of the casing and a valve for closing one end of the second named passage in said piston mounted within one end of the casing in fixed position relative to said piston, and an adjustable spring device 60 engaged with said piston at the end thereof remote from said valve.

6. Mechanism for controlling the flow of fuel 65 and water comprising a casing having a water inlet and outlet and also a fuel inlet and outlet, said casing having a piston therein and said piston having on its periphery a groove movable into and out of communication with said fuel inlet and outlet and at its ends an inlet and outlet chamber and a water passage therethrough from end to end, a valve part in the piston to control the water passage, said valve part being 70 75

movable relative to the piston when the piston moves to open said fuel inlet and outlet.

7. A device of the character described comprising a casing having a cylindrical bore, and 5 water and fuel inlets and outlets, a piston in said bore having a circumferential groove for connecting a fuel inlet and outlet of the casing and said piston also having at one end a valve part movable with the piston to control water through 10 said water inlet and outlet, there being a valve seat held by the casing and flexible means connecting the piston to the casing to allow the piston to move to a position where the circumfer-

ential groove will open the inlet and outlet fuel passages through the casing.

3. In a device of the character described, a casing having a bore therein, said casing also having a stationary valve part held therein, a piston operative in said bore, water and gas inlets and outlets to the casing, said piston having a circumferential groove movable in said bore to open and close a gas inlet and outlet, said piston also having a valve part thereon and a water passage therethrough cooperative with the stationary valve part in the casing to open and close the water inlet. 5 10

ARTHUR R. PANGBORN.
